UNITED STATES PATENT OFFICE.

THOMAS C. THOMAS, OF EVANSTON, ILLINOIS, ASSIGNOR TO THE YOUNGSTOWN SHEET AND TUBE COMPANY, OF YOUNGSTOWN, OHIO, A CORPORATION OF OHIO.

METHOD OF MAKING WELL POINTS.

Application filed March 13, 1926. Serial No. 94,564.

The present invention relates to the manufacture of that class of well points having a tapering head or point integral with the tube or shank of the well point, a principal object 5 of the invention being to provide a novel method of forming the heads as well as a machine adapted for the satisfactory, economical and efficient performance of the said method.

10 The invention further includes various other objects, features and characteristics to which reference is hereinafter more particularly made or which will be apparent from the following description, reference being 15 had to the accompanying drawings forming a part hereof.

In said drawings Fig. 1 is a view of the machine partially in side elevation and partially in vertical section on line 1—1 of Fig. 20 5 looking in the direction of the arrows and with the parts in initial position, that is, in the position in which they are disposed just prior to the machine being put into operation. Fig. 2 is a fragmentary section on line 25 2—2 of Fig. 5 looking in the direction of the arrows with the parts in the same position as in Fig. 1; Fig. 3 is a fragmentary view corresponding to Fig. 1 but showing the parts in final position, that is, the position in 30 35 which they are disposed after the machine has been operated to form the head of the well point, and Fig. 4 is a fragmentary view corresponding to Fig. 2 but showing the parts in such final position. Fig. 5 is a fragmentary front elevation of the machine as shown in Fig. 1; Fig. 6 a vertical section on line 6—6 in Fig. 1 looking in the direction of the arrows, and Fig. 7 is a front elevation of the jaw actuating cross head removed from the machine. Figs. 8, 9 and 10 40 45 are respectively a side elevation, a front elevation and an end elevation of the jaw A removed from the machine, this jaw being similar to its complementary jaw A', and Figs. 11, 12 and 13 are views respectively corresponding to Figs. 8, 9 and 10 but showing jaw B which is similar to its complementary jaw B', jaws A, A' and B, B' being respectively arranged in oppositely disposed 50 55 paired relation in the machine as will hereinafter more fully appear. In Fig. 14 I have shown a blank on an enlarged scale from which a well point is to be formed by the action of the machine and ready for introduction in the latter, and in Fig. 15 I

have shown a well point as it appears after it has been formed by the machine. The same symbols are used to designate the same parts in the several figures.

My improved method contemplates the 60 formation of an integral head upon the end of a pipe or tube by first upsetting the end thereof so that it will present a hollow cross section preferably of greater external and internal diameter than the corresponding diameter of the pipe and then progressively applying about the exterior perimeter thereof of an increasing, radial inwardly directed pressure to effect a consolidation and progressive cross sectional reduction of said upset portion, with resulting formation of an elongated tapering point, solid for a considerable distance in the rear of its smaller extremity and hollow in the vicinity of its juncture with the shank of the well point. 65 This method of forming well point heads I believe to be broadly new and I therefore do not desire to limit myself solely to the use of the machine now to be described for effecting its performance although I have found under practical conditions of operation that the said machine is well adapted therefor; moreover, while the said method lends itself to the production of well point heads of both 70 75 polygonal and circular cross section, it is particularly adapted for the production of the former, and I shall therefore herein refer more particularly to one form of machine intended for the production of tapering well point heads of octagonal cross section in accordance with the principles of 80 85 90 said method.

The said machine as illustrated in the accompanying drawings comprises a rectangular frame having a bottom 1, top 2, sides 3 and 4 and a back or rear wall 5, being open at the front opposite the rear wall. This frame may be supported in any convenient manner as on a base or pedestal 6 which I have shown as of conventional design, its particular configuration being a matter of choice. The top, bottom and side walls of the frame are each provided with a pair of inwardly directed spaced lugs respectively designated as 1'—1', 2'—2', 3'—3', 4'—4' in 95 100 105 correspondence with the designations of the walls to which they are attached and with which they are preferably integral. Each pair of lugs is symmetrically disposed with respect to a plane passing through middle 110

point of the adjacent portion of the frame and is drilled transversely for the passage of a pivot pin 7, these pins being respectively adapted to pivotally support the jaws A, A', 5 B, B' in such manner that the jaws A, A' are in vertical alignment and the jaws B, B' in horizontal alignment with each other. The particular shape and conformation of the jaws will hereinafter be more fully explained. 10

Means are provided for simultaneously moving all of the jaws on their pivots, said means comprising a cross head 10 having a base 11 conveniently in the form of a symmetrical cross at each corner of which are disposed forwardly projecting lugs extending at right angles to each other and transversely drilled for the passage of pins 12. The width of the arms of the base is such 20 that the space between the lugs on the opposite sides of each arm is just sufficient to snugly receive one of the jaws, each of which beside being drilled as at 13 for the passage of the pivot pin is also provided 25 with a slot 14 for the passage of the pin 12, this slot being of sufficient width to accommodate the pin and of sufficient length to prevent the pin from binding on the ends of the slot when the jaw is swung about the 30 pivot pin 7. Preferably the cross head is cast or otherwise formed as an integral unit and provided with an internally threaded bore at the center of its base for the reception of the correspondingly threaded end of 35 a piston rod 15 which extends rearwardly through a hole in the wall 5 and through the medium of which power is supplied to the head so as to move the jaws.

For actuating the piston rod a piston 16 is mounted on the outer end thereof and disposed in a suitable closed cylinder 17 which is bolted to and supported from a housing 18 secured to the rear wall of the frame, the rod, where it enters the front end of the cylinder, preferably extending through a stuffing box having an adjustable gland 19 and operative to prevent leakage around the rod, the housing being provided with holes 20 to afford convenient access to the gland. As 40 the stuffing box may be of any desired form and construction, further description thereof would be superfluous. The cylinder 17 may be provided with pipes 21 and 22 through which steam, air or other suitable 45 fluid may be admitted alternately to the ends of the cylinder so as to reciprocate the piston therein to move the cross head and cause the jaws to simultaneously turn on the pivot pins 7.

60 It will, however, be understood that while means of the general character of those which I have shown and just described are satisfactorily operative to effect the desired movement of the jaws with sufficient power 65 to cause the latter to perform their intended

function as hereinafter explained, various other means may be employed for the purpose should it be so desired, the ultimate end to be effected being the application to the jaws through the medium of pins 12 or equivalent means of a powerful thrust in a direction to cause the jaws to simultaneously swing about their respective pivots from the position shown in Figs. 1 and 2 toward the open end of the frame for a suitable distance. 75

Referring now more particularly to the specific construction of the jaws, reference may first be had to Figs. 8, 9 and 10 illustrating the jaw designated as A and of which, as hitherto stated, jaw A' is a counterpart so that a description of one of them is equally applicable to the other. As shown, each of these jaws comprises a front edge or face 25 and rear edge or face 26, which may extend in more or less parallel relation, and an end face 27 at the extremity of the jaw opposite to that which is bored at 13 for the passage of pivot pin 7. This end face 27 is curved on an arc which is concentric with the bore 13 and upon this face and extending above its surface from one end thereof to the other is disposed a rib 28 preferably slightly narrower in width than the end face 27 so that a narrow shoulder is formed on 85 each side of the rib at the base thereof. The end face 29 of the rib, however, which forms the operative face of the jaw, is not concentric with the bore 13 but is curved rearwardly from the edge 25 to the edge 26 on an arc 90 whose center is somewhat offset from the center of the bore 13, in consequence of which the edge 26 of the jaw is somewhat longer than the edge 25. 95

In Figs. 11, 12 and 13 I have illustrated 105 the jaw B of which jaw B' is a counterpart so that the following description is equally applicable to either of these jaws. The body of this jaw corresponds in shape and size to that of jaw A and similarly thereto has a front edge or face 30, rear edge of face 31 and an end face 32 which follows an arc whose center of curvature coincides with the center of the bore 13. Also, as in the case of jaws A, A', a rib 33 is disposed on the end 110 face 32 which rib at its end adjacent edge 30 is of substantially the same width as rib 28 and is curved rearwardly from said end toward the edge 31. Instead, however, of the 115 sides of the rib being parallel as in the case of rib 28, the sides of the rib 33 may converge inwardly from front to rear (see Fig. 13) while the operative face of the rib instead of being flat as in the case of rib 28 120 is provided with a groove of polygonal cross section of greatest size at the front end of the rib and of smallest size at the rear end thereof, so that the said operative face of the rib is substantially in the form of a trough 125 or groove of decreasing size, that is, taper- 130

ing, from front to rear, with its bottom 34 curved from front to rear on the same arc as the operative face 29 of the rib 28 and its edges 35 curved on a slightly different arc so that the groove is deeper at the front than at the rear.

When intended for the production of well point heads of octagonal cross section, the operative faces of jaws B, B' will be formed 10 to present, as shown in the drawings, a groove having three faces, that is, a bottom 34 and oppositely and angularly disposed faces 36 each of which, as will be apparent from the foregoing description, is tapered 15 from front to rear. Thus when the jaws are operatively assembled in the machine with jaws A, A' in oppositely disposed paired relation and jaws B, B' in similarly paired relation as best shown in Fig. 5, a 20 symmetrical octagonal opening O will be defined by the proximate operating faces of the jaws, three sides of said opening being bounded by each of the jaws B, B' and one side thereof by each of the jaws A, A', the 25 center of the opening being equidistant from the pivotal axes of the several jaws. When the jaws are in initial position this opening is defined and completely bounded by the front ends of the operating faces and is thus 30 of maximum size, but as the jaws move inwardly toward a common center from such position to final position, the opening, by reason of the longitudinal curvature of the faces from front to rear on an arc eccentrically disposed with respect to the pivotal 35 axis of each jaw as hitherto described, becomes gradually smaller, so that when the movement of the jaws is completed, the opening is defined and completely bounded by 40 the rear ends of the operating faces and is of minimum size.

The machine having been constructed and assembled substantially as described and suitable arrangements made for admitting 45 fluid to the cylinder so as to reciprocate the piston, the operation of the machine in the production of a well point head of polygonal cross section in accordance with my improved method is as follows: The end of 50 the pipe or tube from which the well point is to be made is first upset in any suitable manner so as to bring the end of the tube to hollow polygonal form, preferably with an internal and external diameter in excess of 55 that of the corresponding diameters of the pipe, and with a number of plane faces extending parallel to the axis of the tube corresponding to the number of faces which the head of the well point is to have, for example, eight, each of these faces being substantially equal to the greatest width of any of the operative faces, as 34 or 36, of the 60 jaws B, B'. A blank of this general character is illustrated in Fig. 14.

65 The upset end of the blank, being heated to

a suitable temperature to render it semi-plastic and readily workable, is then inserted in the opening O defined by the proximate operative faces of the jaws when in initial position as shown in Figs. 1 and 2 and power 70 applied to the piston in a direction to move the jaws forward about their respective pivots, thus bringing a simultaneous pressure on each of the faces of the upset end of the blank directed inwardly and radially 75 with respect thereto and progressively increasing as the jaws move outwardly. Additionally it will be apparent that during the movement of the jaws and owing to the longitudinal rearward curvature of their operative faces along arcs which are eccentrically disposed with respect to their pivotal axes, a camming action is exerted on the blank as well, the several forces so applied by the 80 jaws resulting in the consolidation of the upset open-ended portion of the blank into an elongated tapering point, solid for a considerable distance in rear of its smaller extremity and having tapering faces in number equal to that of the blank, the size of 85 the head or point where it joins the tube corresponding substantially with the size of the opening O defined between the jaws when in initial position, the size of the smaller end corresponding substantially to 90 the size of the opening defined by the jaws in final position and the length of the head substantially corresponding to the length 95 of the operative faces of the jaws when developed into a plane.

100 While it is sometimes possible to completely form the head by a single movement of the jaws from initial to final position, it is ordinarily requisite to impart to the jaws a series of successive reciprocating movements to fully form the head, the blank between each forward movement of the jaws being pushed inwardly toward the rear of the machine as its cross sectional area is progressively reduced. Thus if the jaws are 105 reciprocated relatively rapidly their successive contacts with the blank produce in effect a series of rapid blows with the result that the formation of the point is completed in a very short space of time after the introduction of the blank into the machine.

110 Although the machine which I have illustrated and described herein is particularly intended for the production of well point heads of polygonal cross section, it may be readily adapted for the production, in accordance with my improved method of well point heads of circular, elliptical or other curvilinear cross section by the employment of jaws whose operating faces are formed 115 to present tapering grooves of arcuate cross section.

120 Additionally, it will be understood that while for convenience of description I have herein employed certain terms such as front,

rear, top, bottom and the like, the same are used solely in a relative as distinguished from a limiting sense and are to be read accordingly.

5 Moreover, while to enable those skilled in the art to readily comprehend and practice the invention, I have herein described my improved process and one form of machine adapted for its performance with considerable particularity, I do not thereby intend to limit myself to the use of any specific form of means or apparatus for performing the process nor, when a machine of the general character of that to which I have referred is used therefor, to any specific details of form, arrangement or construction of the parts thereof as the said machine may be modified in certain particulars to better adapt it for employment under given operative conditions or with a view to producing well point heads of different shapes or for other reasons as may be desired, without departing from the spirit and scope of the invention as defined by the appended claims.

15 Having thus described my invention, I claim and desire to protect by Letters Patent of the United States:

1. The method of forming well point heads which comprises upsetting the end of a pipe or tube so that said upset portion presents a greater diameter than the pipe, and then applying to the exterior surface of said upset portion increasing radial inwardly directed pressure to effect consolidation and progressive cross sectional reduction of said upset portion with resulting formation of an elongated tapering point, solid at its smaller extremity.

2. The method of forming an integral head on the shank of a well point which comprises the steps of upsetting the end of a pipe or tube so as to increase its exterior and interior diameter above the corresponding diameters of the pipe, and then applying to the exterior surface of said upset portion a progressively increasing, radial, inwardly directed pressure to thereby effect a progressive consolidation and cross sectional reduction of said portion with resulting formation of said portion into an elongated tapering point solid at its smaller extremity and hollow adjacent its point of juncture with the pipe.

3. The method of forming well point heads which comprises the steps of upsetting the end of a pipe or tube so as to increase its exterior and interior diameters above the corresponding diameters of the pipe, and then compressing said upset portion by simultaneously applying, initially at its open end and then progressively toward its opposite end, a progressively increasing radially inwardly directed force at all points about its perimeter to thereby form and consolidate said portion into an elongated taper-

ing head solid at its smaller end and hollow adjacent its larger.

4. The method of forming a tapering integral head of polygonal cross section on the shank of a well point which comprises the steps of upsetting the end of the pipe or tube which is to form the shank so that said upset portion will present a hollow polygonal cross section and then simultaneously applying to the exterior surface of each of the faces of said portion an inwardly directed radial pressure to effect consolidation and progressive cross sectional reduction of said portion.

5. The method of forming a tapering integral head of polygonal cross section on the shank of a well point which comprises the steps of upsetting the end of the pipe or tube which is to form the shank so that said upset portion will present a hollow polygonal cross section of greater interior and exterior diameters than the corresponding diameters of the pipe and then simultaneously subjecting all of the exterior faces of said upset portion to radial, inwardly directed pressure to thereby effect consolidation and progressive cross sectional reduction of said portion and form the same into an elongated tapering point.

6. The method of forming a tapering integral head of polygonal cross section on the shank of a well point which comprises the steps of upsetting the end of the pipe or tube which is to form the shank so that said upset portion will present a hollow polygonal cross section of greater exterior and exterior diameters than the corresponding diameters of the pipe and then simultaneously subjecting all of the exterior faces of said upset portion, initially at the open end of said portion and thereafter progressively toward the opposite end thereof, to radial, inwardly directed, progressively increasing pressure to thereby effect consolidation and progressive cross sectional reduction of said portion and form the same into an elongated tapering point solid at its smaller extremity and hollow adjacent its juncture with the pipe.

7. The method of forming well point heads which comprises the steps of upsetting the end of a pipe or tube so as to increase its exterior and interior diameters above the corresponding diameters of the pipe, and then compressing said upset portion by applying, initially at its open end and then progressively toward its opposite end, radially inwardly directed pressure at all points about its perimeter to thereby form and consolidate said upset portion into an elongated tapering head.

In witness whereof, I have hereunto set my hand this 2d day of March, 1926.

THOMAS C. THOMAS.

Certificate of Correction.

Patent No. 1,625,840.

Granted April 19, 1927, to

THOMAS C. THOMAS.

It is hereby certified that error appears in the printed specification of the above-numbered patent requiring correction as follows: Page 4, line 101, claim 6, for the word "exterior" read *interior*; and that the said Letters Patent should be read with this correction therein that the same may conform to the record of the case in the Patent Office.

Signed and sealed this 10th day of May, A. D. 1927.

[SEAL.]

M. J. MOORE,
Acting Commissioner of Patents.
